FUEL CONTROL DEVICE

Guy E. Beardsley, Jr., West Hartford, Conn., assignor, by mesne assignments, to Bendix Aviation Corporation, South Bend, Ind., a corporation of Delaware

Original application November 3, 1939, Serial No. 302,749. Divided and this application December 8, 1944, Serial No. 567,265

25 Claims. (Cl. 123—119)

1

This application is a division of my application Serial No. 302,749, filed November 3, 1939.

This invention relates to improvements in fluid ratio controlling devices and has particular reference to an improved control for the fuel air ratio of an internal combustion engine.

An object of the invention resides in an improved control apparatus operative to automatically proportion the amount of fuel supplied to the engine to the amount of engine intake air.

A further object of the invention is to automatically proportion the total amount of fuel distributed by an engine fuel distributor to the total amount by weight of air taken in by the engine.

A further object resides in the provision of an improved manually controllable engine intake air and fuel supply means in which the fuel supply means is automatically operative to accurately proportion the amount of fuel supplied to the engine to the mass flow of engine intake air, that is, the mass or weight rate of flow per unit of time, supplied under said manual control under normal power operation and to supply sufficient fuel to said engine to maintain engine operation when said manual control is in its engine idling position.

A still further object resides in an improved control apparatus for an engine of the fuel injection type in which the air supply to the engine is manually controlled and the quantity of fuel distributed to the engine by a fuel injection pump or similar distributor is automatically controlled in accordance with the weight rate of air being supplied to the engine.

Still another object resides in an improved fuel control apparatus for an engine of the fuel injection type in which the injection pump for distributing separate and distinct fuel charges to the engine utilizes a fuel pressure variably controlled in accordance with the ratio of the weights of air and fuel supplied to the engine for regulating the position of the element controlling the quantity of fuel delivered to the engine by the injection pump.

Other objects and advantages will be more particularly pointed out hereinafter or will become apparent as the description proceeds.

In the accompanying drawing there is illustrated, by way of example, one embodiment or mechanical arrangement for the purpose of disclosing the invention. The drawing, however, is for the purpose of illustration only and is not to be taken as limiting or restricting the scope of the invention as it will be apparent to those skilled in

2

the art that various changes may be made in the illustrated arrangement without in any way exceeding the scope of the invention.

In the drawing there is shown a diagrammatic illustration of an engine intake air conduit provided with a manual control and one form of engine fuel supply control for proportioning the amount of fuel supplied to the engine to the mass flow of intake air through said intake conduit, 10 certain parts of the device being shown in section to better illustrate the construction thereof.

Referring to the drawing in detail, the numeral 10 generally indicates an engine intake air conduit open at one end to the atmosphere or connected at that end to a supercharger, not illustrated, and provided intermediate its length with a manually controllable throttle, which may be in the form of a butterfly valve 12, manually operable by the movable link 14 connected by means of the lever arm 16 with the valve shaft 18. At its end past the throttle 12 in the direction of airflow this conduit may be connected with an engine supercharger intake, or intake manifold, 20 by some suitable means, such as the overlapping flanges 21 and 22.

Near its intake end the conduit 10 is provided with a restriction in the form of a Venturi tube 24. The tube 24 is provided with an annular channel 26 in the portion of the exterior of the tube which fits into the intake conduit 10 and this channel is connected by means of the radial ports 28 with the interior of the venturi at or near the point of greatest restriction.

A hollow casing 30, which may be of cylindrical form, having closed ends 32 and 34 and a transverse partition 36 is connected to and supported upon the intake end of the intake conduit 10 by suitable means such as the bracket 38, illustrated as formed integrally with the open end of the intake conduit. The interior of the casing 30 is divided by the partition 36 into two separate chambers 40 and 42 and the upper chamber is divided transversely by a movable diaphragm 44 while the lower chamber is similarly divided by a movable diaphragm 46. Both of the diaphragms, 44 and 46, are centrally connected to a movable stem 48 which passes through the partition 36 and extends at its upper end through a slide valve plunger 50 reciprocable in a closed cylinder 52 formed or secured upon the upper surface of the casing end 32 in substantially concentric relation therewith.

The main fuel supply is led under pressure from a fuel supply pump, through a conduit 54 and passage 56 to an annular channel 58 provided in

the inner wall of the cylinder 52. The reciprocable valve plunger 50 is provided with an annular groove 60 adapted to register with the groove or channel 58 when the plunger is in a predetermined position. The plunger 50 is provided with a plurality of apertures or channels 62 which extend from the space between the plunger and the closed upper end of the cylinder 52 to the space between the end 32 of the casing 30 and the upper diaphragm 44 and these channels are connected with the groove 60 by suitable transverse ports 64. From this description it will be apparent that whenever the plunger 50 is in position so that the groove 60 registers in whole or in part with the channel 58 fuel will flow from the conduit 54 and passage 56 into the portion of the chamber 40 above the diaphragm 44 and that the plunger 50 will always have equal pressures acting on its opposite ends because of the provision of the through channels 62.

The fuel flows from the portion of the chamber 40 above the diaphragm 44 through an orifice or restriction 66 controlled by a needle valve 68 to the conduit 70 which leads to the intake of a fuel distributing device such as a fuel injection pump, generally indicated at 72. The device 72 has not been illustrated in detail but, for the purpose of disclosing the invention, is shown as representing any one of various forms of conventional plunger-type fuel injection pumps commonly employed to inject separate and distinct charges of fuel directly into the cylinders of internal combustion engines, through conduits such as 124, in timed relation with the engine. The application of the invention, however, is not limited to any particular form of pump as the control may be applied to other forms of fuel distributing devices.

In the illustrated construction a casing 74 is secured to, or in position relative to, the pump 72 and contains an expandable chamber element which may be in the form of a sealed bellows 76 rigidly connected at one end to the casing 74 and connected at its movable end through a pivoted link 78 with the control arm 80 of the pump 72. The control arm 80 may operate to vary the amount of fuel distributed by the pump or distributor 72 in any suitable manner such as by changing the effective stroke of its piston-type plungers in a manner well known to the art. Movement of the bellows 76 in an expanding direction to increase the stroke of the pump may be resiliently resisted by a suitable compression spring 82. The interior of the bellows 76 is connected through the branch conduit 84 with the conduit 70 leading from the fuel chamber 40 to the intake of the pump 72 so that the pump is controlled in accordance with the pressure of the fuel in the conduit 70. The pressure of the fuel in the conduit 70 is controlled in accordance with the mass airflow through the intake conduit 10 by the mechanism contained in the casing 34 and associated therewith in a manner which will presently appear.

The end of the fuel conduit 70 which connects with the casing 34 is connected by means of a substantially unobstructed passage 86 with the space in the chamber 40 below the diaphragm 44.

The valve 68, cooperating with the orifice 66, is an idling control valve and remains open during power operation of the engine so that the chamber 40 is connected with the fuel conduit 70 through the orifice and the passage 86. With a flow of fuel through the line 70 a pressure dif-

ferential will be created in the chamber 40 upon the opposite sides of the diaphragm 44, the pressure above the diaphragm being somewhat higher than the pressure below the diaphragm because of the obstruction of the orifice 66 in the passage leading from the space above the diaphragm. This pressure differential tends to move the diaphragm 44 downwardly to close the valve 50.

The chamber 42 containing the diaphragm 46 is connected with the interior of the air intake 10 through the two passages 88 and 92 disposed one upon each side of the diaphragm. The portion of the space 42 above the diaphragm 46 is connected by the passage 88 with the annular groove 26 surrounding the throat of the venturi 24 while the portion of the space 42 below the diaphragm 46 is connected by the passage 92 with the space in the intake duct 10 ahead of the venturi 24 in the direction of air flow. Since the air pressure at the throat of the venturi is less than the pressure of the air in the relatively unrestricted portion of the intake duct on the upstream side of the venturi when air is flowing through the venturi 24 and intake duct 10, a pressure differential upon opposite sides of the diaphragm 46 since the pressure in the channel 88 connected with the venturi throat will be less than the pressure in the channel 92 connected with the unrestricted portion of the intake duct on the upstream side of the venturi. This pressure differential will tend to move the diaphragm 46 upwardly in a direction to open the valve 50.

It will thus be seen that two opposing forces exist both of which act on the stem 48, one tending to move the stem to close the fuel valve 50 in response to a pressure differential on the diaphragm 44 created by and varying as a function of the flow of fuel through the orifice 66, and the other tending to open the fuel valve 50 in response to a pressure differential on the diaphragm 46 created by and varying as a function of the flow of air through the venturi 24. Since the fuel flow is controlled by the location of the fuel valve 50 these two opposing forces will balance each other at a certain relationship of fuel flow to airflow. The physical laws governing the flow of liquid and the flow of gasses through fixed restrictions indicate that this relationship will remain substantially constant over a wide range of rates of flow.

Since an aperture 98 has to be provided in the partition 36 for the passage therethrough of the stem 48 it is necessary to provide some means to separate the space 40 from the space 42 while still permitting free movement of the stem 48. Such means may conveniently take the form of a flexible seal member 94 sealed at one end to the partition 36 surrounding the aperture 98 and sealed at its opposite end to the upper surface 60 of the diaphragm 46. The unbalancing force on the diaphragm 46 caused by the area of the interior of this seal member, connected with the portion of the space 40 below the diaphragm 44, may be counterbalanced by a similar seal member 96 sealed at one end to the undersurface of the diaphragm 46 and sealed at its opposite end to the bottom wall 34 of the chamber 30 and having its interior connected through the conduit 100 with the space in the chamber 40 above the diaphragm 44, the internal area of the seal 96 being the same as the internal area of the seal 94.

With this arrangement there is an area of the diaphragm 44 subjected to an upward force and an equal area of the diaphragm 46 within the seal 94 subjected to an equal downward force

which two forces exactly cancel each other since the two diaphragms are rigidly connected together by the stem 48. Similarly there is a downward force on an area of the upper surface of the diaphragm 44 which is exactly cancelled by an upward force on the lower surface of an equal area of the diaphragm 46 within the flexible seal 86. Thus areas of both diaphragms 44 and 46 equivalent to the areas of the flexible seals 84 and 86 are mutually balanced so that the effect of fluid pressure on these areas does not effect the valve controlling operation of the diaphragms. In other words, by the arrangement shown, the seals merely reduce the effective areas of diaphragms 44 and 46, the pressures in each of the spaces above and below diaphragms 44 and 46 being effective over a net diaphragm area equal to the area of the diaphragm minus the area of the seal.

Since the regulation of the fuel flow is accomplished entirely by differential pressures it follows that the absolute values of the fuel pressure in the line 70 does not affect the metering of the fuel by valve 50. On the other hand, the pressure of the fuel in line 70 will be transmitted through line 84 to the interior of the bellows 76 wherein the pressure of the fluid tends to expand the bellows against the force of the spring 82. Any movements of the free end of the bellows occasioned by changes in the pressure of the fuel within the bellows is transmitted through the link 78 to the pump regulating arm 80.

With the engine operating in equilibrium with the fuel and air being properly proportioned the air differential pressure on diaphragm 46 will be balanced by the fuel differential on diaphragm 44. If now the air flow to the engine should increase, as by opening of throttle 12, the air differential pressure across diaphragm 46 will increase thereby urging stem 48 upwardly to further open valve 50. As more fuel is then being passed through valve 50 into the conduit 70 than is being withdrawn from the conduit 70 by the pump 12, there will be a pressure rise in the conduit 70 and a consequent expansion of the bellows 76 producing an increase in the stroke of the pumps. This increasing of the pump stroke will continue until the pumps are taking away as much fuel from the conduit 70 as is necessary to create a pressure drop across orifice 66 and diaphragm 44 which will balance the air pressure differential across diaphragm 46, whereupon the fuel to air ratio supplied the engine will be re-established or maintained at its desired value and the stem 48 and its diaphragm assembly will again be in equilibrium. Similarly if the flow of fuel through the metering valve 50 falls below the capacity of the pumps at a particular stroke setting, as will occur upon closing of the throttle 12 and resulting closing movement of valve 50, the pressure in conduit 70 will decrease and a readjustment of the pump stroke will be accomplished to reduce the pump capacity such that the flow through the metering valve and metering orifice will be just sufficient to reestablish equilibrium of the fuel and air differential pressures acting on diaphragms 44 and 46. Substantially constant fuel to air proportioning is thus obtained.

When the engine speed is very low, as when the engine is operating in the idling range, an enriched mixture is desired. In addition, during idling the mass flow of air through the air intake and venturi will be so small as to create only a very slight pressure differential in the chamber 42 on the opposite sides of the diaphragm 46,

which pressure difference, while theoretically effective to continue the control of the metering valve 50, is practically undependable because of frictional effects and other factors of resistance in the mechanism. Therefore, in order to insure a steady and sufficient supply of fuel in the low speed range a suitable resilient member, such as the coil spring 102, is disposed below the diaphragm 46 to resiliently urge the valve 50 to partially open position. This spring may conveniently be disposed in the lower seal member 86 as illustrated and exerts a force which is in addition to and in the same direction as the force created on stem 48 by the air differential pressure on diaphragm 46. An increased fuel flow is thus provided such that the force created on stem 48 by the fuel differential pressure on diaphragm 44 is sufficient to balance both the air force and the spring force. The mixture richness is thus increased at idle as is desired. The spring force is, however, comparatively slight since the force exerted by the fuel differential tending to close the valve is very low in the engine idling range as the engine consumes but a small amount of fuel when idling. Since, however, the force exerted by the fuel flow pressure differential on the diaphragm 44 when the engine is operating in its power range is comparatively large, the ratio of the fuel flow pressure differential force to the spring force becomes so large in the power range that the spring force may be neglected and the resultant of the fuel differential force and air pressure differential force relied upon to control the fuel metering operation of the fuel valve 50.

It has been found desirable to select an idle spring 102 of a strength sufficient to provide an excessive enrichment at idle and then to decrease the enrichment by using a throttle controlled valve arranged to restrict the effective area of the metering orifice 66 as the throttle approaches idling position thereby making available any desired idle and near idle enrichment. This is accomplished by the valve 68 which is operatively connected with the throttle valve shaft 18 by means of the link 118 and levers 120 and 122. The valve 68 and its operating elements are so constructed and arranged that the valve does not begin to restrict the orifice 66 until a low engine speed throttle setting is reached at which the effect of the spring 102 becomes important in controlling the operation of the valve 50. At all smaller throttle openings and hence all lower engine speeds the fuel is metered to the engine by the valve 68 operating in conjunction with the orifice 66 and the metering valve 50 and the air and fuel flow at these low speeds is controlled primarily by the position of the throttle 12 and the valve 68 rather than by the effect of mass airflow through the venturi 24 on the diaphragm 46. This method operates effectively for the low speed throttle settings indicated since at each such throttle setting the mass flow of intake air through the engine remains substantially constant and a constant fuel supply is, therefore, required. Although changes in the engine load such as are occasioned by changes in the pitch of the engine driven propeller or changes in the flying attitude of an engine carrying airplane may cause the engine speed to vary within relatively wide limits, the mass airflow to the engine remains substantially constant for these various engine speeds because of the well known physical law of gas flow to the effect that, when gas is flowing through a conduit having a restriction therein,

further decreases in the pressure of the gas in the conduit beyond the restriction in the direction of flow from a value approximately one-half the pressure in the conduit ahead of the restriction do not increase the rate of flow through the conduit. Thus, since with throttle settings in the engine idling range, the pressure ahead of the throttle is normally more than twice the pressure beyond the throttle, the airflow will remain substantially constant for any particular throttle setting regardless of variations in engine speed.

It is a circumstance well known to the art that the density of atmospheric air decreases with increases in altitudes, and that the reduction in pressure at the throat of a venturi for any given mass airflow therethrough varies in inverse proportion to the square root of the air density. This indicates that the same mass airflow through the venturi will not produce the same pressure drop at the Venturi throat if the altitude varies with a consequent variation in atmospheric air density and that it is necessary, therefore, to incorporate an altitude compensating device in any apparatus designed to function in accordance with mass airflow if the apparatus is to function correctly at different altitudes.

The following description is illustrative of one manner in which the necessary altitude compensation can be accomplished.

A restriction or orifice 90 is disposed in the channel 88 and a channel 104 is provided interconnecting the channels 88 and 92 and having a restriction or orifice 106 therein. The opening through the orifice 106 is controlled by a needle valve 108 operated through a suitable leverage, including the links 110 and 112 and the bellcrank 114, by an expandible element 116 disposed in the air intake conduit adjacent to the intake end of the venturi 24 and responsive to changes in the density of the air surrounding it. When the density of the air in the intake ahead of the venturi is at normal sea level temperature and pressure, the expandible element 116 is contracted until the needle valve 108 closes the aperture 106, in which case the restrictions 106 and 90 are inoperative and the diaphragm 46 is subject directly to the pressure difference between the air pressure ahead of the venturi and the pressure at the Venturi throat. If the air in the intake ahead of the venturi is at a density less than that of the air at sea level the element 116 will expand and move the valve 108 to open the orifice 106 an amount proportional to the variation of the air density from the density at sea level. With the orifice 106 thus partially open, air will flow through this orifice into the channel 88, to the orifice 90, the annular space 26, and out the openings 28 due to the pressure differential existing along this path. Because of this flow the portion of the channel 88 between the restrictions 106 and 90 will then have a pressure different from either the pressure in the channel 92 or the pressure at the Venturi throat but proportional to both. By properly contouring the needle 108 and selecting the correct sizes for the orifices 106 and 90 it can be so arranged that the pressure differential on opposite sides of the diaphragm 46 is maintained constant for the same mass airflow regardless of the density of the air in the air intake ahead of the venturi, since the space in the chamber 42 above the diaphragm 46 is connected to the portion of the channel 88 between the restrictions 106 and 90.

While but one specific embodiment of the invention has been illustrated in the accompanying

drawing and hereinabove described for the purpose of disclosing the invention, it is to be understood that the invention is not limited to the particular arrangement so illustrated and described, but that such changes in the size, shape and arrangement of the various parts may be resorted to as come within the scope of the subjoined claims. A portion of the subject matter disclosed but not claimed herein is being claimed 5 in the copending application of Frank C. Mock Serial No. 362,572, filed October 24, 1940, a continuation of abandoned application Serial No. 118,718, filed January 2, 1937.

Having now described the invention so that 10 others skilled in the art may clearly understand the same, what it is desired to secure by Letters Patent is as follows:

1. In a direct injection fuel system for an internal combustion engine having an air intake, 20 an injection pump having a plurality of outlets for introducing a measured amount of fuel into respective engine cylinders, a fluid chamber and a fluid pressure responsive element for varying the capacity of said pump to vary the amount of fuel delivered by said pump through said outlets to said engine, a conduit connected with said chamber and with the inlet of said pump, a valve for controlling the admittance of fuel to said conduit, and means for adjusting said valve to 30 maintain the rate of flow by weight of fuel delivered to said engine by said pump in predetermined ratio to the rate of flow by weight of intake air to said engine, said means including a venturi in said air intake for measuring the rate 35 of flow by weight of air to said engine and a metering orifice for measuring the rate of flow by weight of fuel to said pump.
2. In an apparatus for directly injecting liquid fuel into a combustion chamber having an air intake, 40 an injection pump having an outlet conduit associated therewith for delivering liquid fuel to said combustion chamber, adjusting mechanism including a pressure responsive member for varying the pumping capacity of said pump to control 45 the amount of fuel pumped by said pump to said combustion chamber, a fuel inlet conduit connected with said pump and in communication with said pressure responsive member, and means including a fuel flow regulating valve in said inlet conduit upstream of said pressure responsive member for maintaining the amount of fuel by 50 weight per unit of time delivered to said combustion chamber by said pump in predetermined ratio to the amount of air by weight per unit of time 55 passing to said combustion chamber through said air intake, said means also including, a fuel metering orifice in said inlet conduit for measuring the rate of flow by weight of fuel to said pump, a venturi in said air intake for measuring the rate 60 of flow by weight of air through said air intake, and means for actuating said fuel valve in accordance with variations in the pressure drop across both said fuel orifice and said venturi.
3. A fuel injection apparatus for an internal combustion engine having an air intake and a throttle valve, including, an injection pump having a plurality of outlets for distributing liquid fuel among respective engine cylinders, fuel pressure responsive means connected with the mechanism of said pump operative to vary the amount of fuel delivered by said pump through said outlets to said engine, and control mechanism operatively associated with said fuel pressure responsive means to maintain the rate of flow by weight 75

of fuel delivered to said engine by said pump in predetermined ratio to the rate of flow by weight of intake air to said engine, said control mechanism including, a venturi having an air density compensating device associated therewith for establishing an air pressure difference which is a measure of the rate of flow by weight of air to said engine, metering means for establishing a fuel pressure difference which is a measure of the rate of flow by weight of fuel through said pump, a valve for regulating the flow of fuel to said pump, means for operating said valve by both said air pressure difference and said fuel pressure difference, and mechanism connected with said throttle for controlling the fuel flow through said metering means in accordance with the position of said throttle.

4. An apparatus for pumping and regulating the flow of liquid fuel at a pressure and for the direct injection of said fuel into an engine cylinder having an air intake, comprising, an injection pump having a relatively high pressure fuel outlet for introducing a measured amount of fuel into said engine cylinder, means for supplying fuel at a pressure lower than the injection pressure to said injection pump, a metering device interposed between said supply pump and said injection pump, said metering device including means for measuring the rate of flow of fuel by weight to said injection pump and the rate of flow of air by weight to said air intake and a fuel valve for controlling the rate of flow by weight of fuel from said fuel supply means to said injection pump in predetermined ratio to the rate of flow by weight of air to said air intake, adjustable means for varying the amount of fuel pumped by said injection pump to said engine cylinder, and fuel pressure actuated means for adjusting said adjustable means in response to variations in the relation between the rate of flow of fuel through said valve to said injection pump and the rate of flow of fuel from said injection pump to said cylinder.

5. In combination, a fuel injection pump having a plurality of outlet conduits associated therewith for distributing liquid fuel among the cylinders of an internal combustion engine having an air intake, means for feeding fuel to said pump, means for varying the rate of flow of fuel fed to said pump in predetermined relation to the rate of flow by weight of air flowing to said engine through said intake, and mechanism responsive to variations in the relation between the rate of flow of fuel to said pump and the rate of flow of fuel from said pump for varying the capacity of said pump in accordance with said variations in the ratio of said fuel flow rates.

6. In a direct injection fuel system for an internal combustion engine having an air intake, an injection pump having a plurality of outlets for introducing a measured amount of fuel into respective engine cylinders, a conduit connected to said pump, a valve for controlling the rate of flow of fuel through said conduit, means responsive to the rate of fuel flow through said conduit and the rate of air flow through said air intake for regulating said valve, and mechanism responsive to the pressure in said conduit for increasing the capacity of said pump in accordance with increases in said pressure and for decreasing the capacity of said pump in accordance with decreases in said pressure.

7. In a system for supplying fuel and air to a fuel injection engine, an air passage, a venturi in said air passage creating an air differential

pressure, a fuel injection pump, a control for varying the quantity of fuel delivered by said pump, yielding means urging the control in a direction to decrease the pump delivery, means actuated by the pressure of the fuel supplied to the pump for urging the control in a direction to increase the pump delivery, and valve means responsive to the air differential pressure for varying the pressure of the fuel supplied to the pump.

8. In a direct injection charging system for an engine having a combustion chamber and an air intake, an injection pump for delivering a measured amount of a liquid charge into said combustion chamber, a liquid inlet conduit connected to said pump for supplying said liquid thereto, means for regulating the rate of flow of liquid through said conduit in predetermined ratio to the rate of flow of air through said air intake, and means responsive to variations in the pressure of said liquid for varying the capacity of said pump to maintain the amount of liquid delivered by said pump to said combustion chamber equal to the amount of liquid supplied to said pump through said inlet conduit by said flow regulating means.

9. In a system for supplying fuel and air to a fuel injection engine, a main air supply passage, a venturi in said air passage for creating an air differential pressure, a fuel injection pump for intermittently delivering separate and distinct fuel charges to the individual engine cylinders, a control for varying the quantity of fuel delivered by said pump, yielding means urging the control in a direction to decrease the pump delivery, fuel pressure actuated means for urging the control in a direction to increase the pump delivery, and means responsive to the air differential pressure for controlling the fuel pressure actuated means.

10. In combination with an internal combustion engine, a fuel injection pump, an air passage, an element controlling the effective pumping capacity of the pump, an element controlling the air passage, means for manually actuating one of said elements, a movable wall connected to the other element, and means including a fuel pump for supplying fuel to the injection pump and for supplying fuel at a variably controlled pressure to said movable wall for actuating the other element.

11. In combination with a multi-cylinder internal combustion engine, a fuel injection pump having a plurality of pumping members, an element movable to vary the effective pumping capacity of the members for varying the fuel supply to the engine, an air supply passage, an element for varying the air supply to the engine, a manually operable member controlling one of said elements, a movable wall operatively connected to the other element and subjected to fuel under pressure, and means for varying the fuel pressure on the wall to control the said other element.

12. In combination with a multi-cylinder internal combustion engine, an air supply passage, an element controlling said passage, a fuel injection pump driven in timed relation with the engine and having a plurality of pumping members, an element controlling the effective pumping capacity of said members to vary the fuel supply to the engine, manual means for actuating one of said elements, a fuel pressure responsive movable wall for actuating the other of said elements, a fuel conduit supplying fuel to the injection pump, means including a fuel valve for varying the pressure of the fuel on said wall, and means responsive to air pressures at spaced

11

points in the air passage and to fuel pressures at spaced points in the fuel conduit for controlling said valve.

13. The invention defined in claim 12 comprising in addition a sealed capsule responsive to variations in altitude for modifying the control of said valve.

14. In a charge forming device, a fuel injection pump, an air passage, an element controlling the effective pumping capacity of the pump, an element controlling the air passage, means for manually actuating one of said elements, a movable pressure responsive member for actuating the other element, means for subjecting the member to fuel pressure, and means responsive to air pressures varying with the rate of air flow to the engine and to fuel pressures varying with the rate of fuel supply to the engine for varying the fuel pressure on the member to control the said other element.

15. In a charge forming device, an air passage, a differential pressure creating means in the air passage, a throttle in the passage, an element for controlling the throttle, a fuel injection pump, an element for varying the effective pumping capacity of the injection pump, a fuel supply pump, a conduit from the supply pump to the injection pump, a differential pressure creating means in the conduit, means for manually actuating one of the elements, a movable pressure responsive wall operatively connected to the other element, means for subjecting the wall to fuel pressure, and means responsive to the pressures created by the differential pressure creating means in the air passage and in the fuel conduit for controlling the said fuel pressure.

16. In a fuel feeding system for a direct injection engine, a fuel injection pump for intermittently delivering fuel directly to the engine cylinders in timed relation therewith, a fuel conduit for supplying fuel to said pump, area restricting means in the conduit, an air conduit for supplying air to the engine, a venturi in the air conduit for creating an air differential pressure, means for modifying the air differential pressure in accordance with the temperature and pressure of the air in the air conduit, diaphragm means subjected to the modified air differential pressure and to a differential in fuel pressures resulting from flow through the area restricting means, manually operable means controlling the flow through one of the conduits, an element controlling the flow through the other conduit, a pressure responsive movable wall for actuating said element and subjected to fuel under pressure, and means connected to said diaphragm means for varying the fuel pressure on said movable wall to control said element.

17. In a fuel injection system for an engine, a fuel injection pump, a fuel conduit leading from the pump to a cylinder of the engine for supplying individual charges of liquid fuel thereto in timed relation with the engine, a fuel control element for varying the quantity of fuel in the individual charges, an air passage for supplying air to the cylinder, a control element for varying the quantity of air supplied to the cylinder, manual means for actuating one of said elements, a movable pressure responsive wall operatively connected to the other element, means including a fuel conduit for supplying fuel to the pump and to the wall, and means responsive to air and fuel pressures varying in accordance with variations in the flow of fuel and air to the engine for vary-

12

ing the pressure of the fuel on said wall for operating said other element.

18. In a fuel feeding system for a direct injection engine, an air passage for supplying air to the engine, a venturi and a throttle in the passage, an element connected to the throttle, a fuel injection pump for intermittently supplying individual fuel charges to the engine cylinders in timed relation therewith, a movable element for varying the quantity of fuel in the fuel charges a fuel conduit for supplying fuel to the pump area restricting means in the conduit, a valve in said conduit, means responsive to the pressure in the venturi and to the pressures in the fuel conduit anterior and posterior to the area restricting means for controlling said valve, manual means for actuating one of said elements and means responsive to the fuel pressure in said conduit posterior to the valve for actuating the other of said elements.

19. The invention defined in claim 18 wherein a decrease in pressure in the venturi tends to open said valve.

20. In a fuel feeding system, a fuel injection pump comprising a housing and a plurality of fuel pumping units therein receiving fuel from within the housing, a fuel conduit supplying fuel to the housing, means including a movable wall responsive to the pressure of the fuel supplied to the housing for varying the effective pumping capacity of said units, an air supply conduit, and means responsive to pressures resulting from flow through said conduits for varying the pressure of the fuel supplied to said housing to thereby actuate the said capacity varying means.

21. The invention defined in claim 20 comprising in addition means responsive to variation in the pressure of the air entering the air conduit accompanying a change in altitude for varying the pressure of the fuel supplied to the housing.

22. A system for supplying fuel and air to an injection engine, comprising an air passage having a throttle, a venturi in the passage anterior to the throttle for creating an air differential pressure, a fuel injection pump for intermittently injecting separate and distinct charges of fuel into the respective combustion chambers of the engine in timed relation therewith and having a control element for varying the quantity of fuel in said charges, a conduit for supplying fuel to the pump, area restricting means in said conduit creating a fuel differential pressure, a pressure responsive movable wall subjected to fuel pressure operatively connected to said control element, and means responsive to said air and fuel differential pressures for varying the fuel pressure on said wall to actuate said control element.

23. The invention defined in claim 22 comprising in addition means for varying the effective area of the area restricting means.

24. In combination with an engine having an air-intake conduit provided with a throttle and fuel supply means having an output proportional to engine speed and whose output at any given speed is variable, a member movable to control the output of said fuel supply means, automatic fuel-air ratio controlling mechanism functioning to meter fuel to said fuel supply means at predetermined fuel-air ratios for all operating positions of the throttle, and a movable element operatively connected to said member and subjected directly to the metered fuel for regulating the effective delivery of said fuel supply means in response to variations in metered fuel pressure.

25. In combination with an engine having an

air-intake conduit provided with a throttle, a fuel supply means having an output proportional to engine speed and whose output at any given speed is variable, a member movable to control the output of the fuel supply means, automatic fuel-air ratio control mechanism functioning to meter fuel to said fuel supply means at a predetermined fuel-air ratio for each operating position of the throttle and to vary the pressure of the metered fuel upon variation in said fuel-air ratio, and a movable pressure-responsive element operatively connected to said member and subjected directly to metered fuel pressure for regulating the effective delivery of the fuel supply means in response to variations in the metered fuel pressure.

GUY E. BEARDSLEY, JR.

Certificate of Correction

Patent No. 2,447,266.

August 17, 1948.

GUY E. BEARDSLEY, JR.

It is hereby certified that error appears in the printed specification of the above numbered patent requiring correction as follows:

Column 4, line 25, after "differential" insert the words *will be created*; and that the said Letters Patent should be read with this correction therein that the same may conform to the record of the case in the Patent Office.

Signed and sealed this 30th day of November, A. D. 1948.
